ATTORNEY

UNITED STATES PATENT OFFICE

CARL E. ANDERSON, OF EAST ORANGE, NEW JERSEY, ASSIGNOR TO EASTERN TOOL & MANUFACTURING CO., OF BLOOMFIELD, NEW JERSEY

SLIDE

Application filed April 1, 1931. Serial No. 526,816.

This invention relates to an improved slide which provides a smoother and less bulky article when a strap is threaded through it than is provided with the old forms of slides. The 5 slide also enables an economy of material which the strap is made of by means of a clip which is part of the slide and is secured to the end of the strap. My improved slide also enables the quicker and easier assembly of the 10 strap and the slide.

The article also provides a unitary device of a frame and a clip secured together and easily handled for prompt and easy pressing of the clip to fasten it to the strap.

15 The invention is illustrated in the accompanying drawing in which Figure 1 is a front view of the new form of slide secured in place on a strap. Figure 2 is a side view of Figure 1. Figure 3 is a front view of a slide 20 embodying my invention. Figure 4 is a section on line 4-4 in Figure 3. Figure 5 is a fragmentary view showing a modified form for fastening the clip to the frame. Figure 6 is a section on line 6-6 in Figure 5.

25 The slide is particularly adapted for use with apparel. The slide is used in conjunction with a strap 10 which in overalls and the like is made of denim. It is threaded through the frame and then bent back to form 30 a loop 11 and the end is secured to the clip. In the old form the end of the strap was either folded over an arm on the frame and then stitched or it was threaded through in the reverse direction and left with a loose end. 35 The loop 11 is for the suspension of a button loop or a clasp.

The slide is made up as a frame with three parallel strands. I show a frame made of 40 wire and having a top strand 12, a central strand 13 and a bottom strand 14. The frame is not a new feature in itself and any form of strand can be used.

45 The usual forms are made of wire and I show the frame made of wire square in cross section. The side connecting portions or strands 16 are to prevent undue side movement of the strap in the frame.

The clip 17 is used for securing the free 50 end of the strap to the slide. It is made of sheet metal bent in a return bend to form a

loop 18 that embraces a strand of the frame and opposed walls 19 that are pressed together to fasten the clip to the end 20 of the strap.

The opposed walls 19 are pierced to form 55 barbs or prongs 21. They are inwardly inclined toward the loop 18 and are long enough to engage and be partly upset by the opposite wall when the press is used to force the walls to confine the end of the strap. 60 These prongs 21 are within the dimensions of the walls 19 and provide a secure hold when they are spaced apart and the opposed prongs are opposite the spaces as in Figure 1. The 65 ends of the prongs 21 are clinched by engagement with the opposite wall and are therefore preferably of a length to insure this clinching as shown in Figure 2. With this 70 form of slide there is only one thickness of denim in the slide and, furthermore, the denim can be threaded through the end 20 secured to the clip in a fraction of the time heretofore used to fasten the parts together.

In order to facilitate the fastening of the 75 end of the strap, I prefer to make the frame and the clip a unitary device. This is done by forming the strand to which the clip is secured and the clip, with the co-acting means for holding the partly open clip on the frame. I show one form of such means in 80 Figures 3 and 4. The clip is provided with ears 22 which engage the bar 14 while the clip is partly open. (See Figure 4.) This enables the operator to feed the end of the 85 strap into the clip while the clip is held to the frame. All that is necessary to do is to force the two plates 19 together against the strap.

In Figures 5 and 6 I show a modification 90 of such holding means. In this form the clip is perforated as at 23 and the bar 14 is provided with a projection or humped part 24 which holds the clip on the bar even when the clip is open enough to allow the strap to be placed between the plates 19.

The strap can be easily fed lengthwise into the clip as the prongs 21 are staggered and thus not being opposed there is plenty of room for the easy insertion of the strap.

The form of frame can be varied and the 100

clip can be secured to a bar other than the bottom bar but the relationship of the parts as shown is the preferred manner of assembly.

6 I claim:—

1. A slide comprising a frame having three substantially parallel strands, and a sheet metal clip bent over one of the outside strands and having opposed plates each provided with prongs out of alignment with the prongs on the other and of a length to engage the other plate when the clip is compressed to grasp a strap whereby the ends of the prongs are clinched.
- 10 2. A slide comprising a frame having three substantially parallel strands and a sheet metal clip bent over one of the outside strands and having opposed plates each provided with prongs to engage the other plate when the clip is compressed to grasp a strap, the strand and the clip having co-acting means for retaining the clip in the strand when the clip is partly open.
- 15 3. A slide comprising a frame, a clip of sheet metal formed by a return bend into a looped end and opposed plates the looped end having ears bent inwardly to engage the strand and the plates having inwardly extending prongs to be embedded in a strap when the plates are pressed toward each other.
- 20 4. In a slide, a clip of sheet metal formed by a return bend into a loop and opposed plates, the looped part having inwardly bent ears, the opposed plates having inwardly bent prongs.
- 25 5. In a slide, a clip of sheet metal formed by a return bend into a loop and opposed plates, the looped part having inwardly bent ears, the opposed plates having inwardly bent prongs, said prongs being inclined in the direction of the looped end.
- 30 6. In a slide, a sheet metal clip formed by a return bend into a looped end at the top and opposed plates, said plates being pierced above the bottom edge to form spaced prongs, the prongs on one being opposite the spaces on the other and inclined toward the loop and adapted to be upset by engagement with the opposite plate when the plates are compressed against a strap lying between them.
- 35 7. In a slide, a sheet metal clip formed by a return bend into a loop and opposed plates, at least one plate having prongs extending inwardly from one wall and adapted to be engaged by the other wall and clinched at their ends when plates are forced against a strap lying between them.

60 In testimony whereof he affixes his signature.

CARL E. ANDERSON.
